UNITED STATES PATENT OFFICE.

FRANK W. KNOWLES, OF SEATTLE, WASHINGTON.

COMPRESSOR.

Application filed August 24, 1925. Serial No. 52,037.

This invention relates to air or gas compressors, and has more particular reference to improvements in rotary compressors embodying revolving reciprocating pistons.

- 5 The primary object of the present invention is to provide a compressor of the above kind which is extremely simple and durable in construction as well as efficient in operation.
- 10 Another object is to provide a compressor of the above kind which may be cheaply and easily manufactured and assembled with accuracy and without the requirement of special skill or tools.

- 15 A further object is to provide a compressor of the above kind which is so constructed as to not readily get out of order, and wherein a minimum number of anti-friction bearings are required, such bearings 20 being readily accessible for renewal or repair.

With the above general objects in view, and others that will become apparent as the nature of the invention is better understood, 25 the same consists in the novel form, combination and arrangement of parts hereinafter more fully described, shown in the accompanying drawings and claimed.

In the drawings wherein like reference 30 characters indicate corresponding parts throughout the several views,

Figure 1 is a top plan view of a rotary compressor constructed in accordance with the present invention,

35 Figure 2 is a view partly in side elevation and partly in longitudinal section of the device shown in Figure 1,

Figure 3 is a transverse vertical sectional view taken substantially upon line 3-3 of 40 Figure 1,

Figure 4 is a longitudinal sectional view taken substantially upon line 4-4 of Figure 3,

45 Figure 5 is a fragmentary vertical sectional view taken substantially upon line 5-5 of Figure 2,

Figure 6 is a view similar to Figure 5 taken substantially upon line 6-6 of Figure 2,

50 Figure 7 is a fragmentary view partly in elevation and partly in longitudinal section of the stationary shaft or axle about which the cylinders revolve, together with its associated ported rings,

Figure 8 is an enlarged central transverse 55 sectional view of one of the ported rings, and

Figure 9 is a view of the rings shown in Figure 8 taken in central section upon a line at right angles to the plane of section of 60 Figure 8.

Referring more in detail to the drawings, the present invention embodies a cylinder block formed to provide a pair of radial aligned cylinders 5 connected at their inner 65 ends by an intermediate crank case 6 that is formed with axially aligned openings in the sides thereof in which are fitted the inner ends of horizontally arranged and aligned sleeves 7 which are provided with external 70 annular flanges 8 that flatly engage the outer surface of the crank case 6 in surrounding relation to the openings of the latter. The flanges 8 are provided with openings through which pass stud screws 75 9 that are threaded into the crank case for securely maintaining the sleeves 7 in place. The outer ends of the sleeves 7 are freely journaled in aligned anti-friction bearings 10 provided in the upper ends of a pair of 80 spaced uprights or standards 11 which are of sufficient height to insure supporting of the cylinder blocks at the required elevation above the supporting surface of the compressor. The bearings 10 may be of any 85 well known or preferred form and either of the ball or roller type embodying concentric races respectively secured to the cooperating standard 11 and the associated sleeve 7.

The outer ends of the cylinders are closed 90 by means of detachable cylinder heads in the form of plates 12 bolted in place as indicated at 13, and the outer ends of the cylinders are counter-bored to provide internal shoulders as at 14. Slidably fitted in the counter-bored outer portions of the cylinders are relatively shallow cup shaped valves 15 which are yieldingly seated upon the shoulders 14 by means of helical compression springs 16 interposed between the 100 valves 15 and the heads 12.

The cylinder block is provided with passages 17 and 18 which respectively open 105 through opposite sides of the cylinder block adjacent the axial openings in the latter, and the passage 17 communicates with the cylinders 5 and the point inwardly of the shoulders 14 of valves 15, while the passage

18 communicates with both cylinders at points outwardly of the seats 14 of said valves 15 as shown clearly in Figure 3. It is to be noted that the valves 15 fit loosely 5 in the cylinders so that gas may pass around the same from the cylinders to the passage 18 when the valves are unseated, and the points at which the passage 17 communicates with the cylinders are outwardly of 10 the inner limits of movement of pistons 19 which are disposed to reciprocate in the cylinders 5.

The sleeves 7 are provided with passages 20 which respectively communicate at their 15 inner ends with the passage 17 and the passage 18, and which communicate at their outer ends with the interior of the respective sleeves 7 in which they are provided.

A stationary shaft or axle 21 freely extends 20 through the sleeves 7 so that the latter may freely rotate thereon, and this shaft is provided with a pair of longitudinal passages 22 and 23 that terminate in radial portions disposed to communicate with radial 25 openings 24 provided in channel shaped rings 25 that are disposed upon the shaft 21 within the sleeves 7.

The bores of the sleeves 7 are enlarged in 30 the major outer portions of the latter so as to provide a packing space between the same and the adjacent portions of the shaft 21, and the rings 25 are disposed in the intermediate portions of these packing spaces of the sleeves 7 and have packing rings at opposite sides thereof. These packing rings closely fit about the shaft 21 and within the sleeves 7 and are generally indicated at 26 although they preferably embody alternate rings of metallic packing and rings of flax 10 impregnated with graphite. In this way, spaced metallic bearings are formed by the packing rings with intermediate lubricating packing rings so that friction is reduced to a minimum. The packing and the rings 25 45 are maintained in place by means of tubular glands 27 which are threaded into the outer ends of the sleeves 7, and by reason of this construction leakage of air or gas between the sleeves 7 and the shaft 21 into the crank 50 case 6 or outwardly to the atmosphere may be effectively prevented.

It will be seen that the cylinders are completely supported by the sleeves 7 and standards 11 so that no anti-friction bearings 55 of the ball or roller type are required between the shaft 21 and the sleeves 7. It is simply necessary to provide any suitable means to restrain the shaft 21 from rotating, and the only anti-friction bearings employed 60 are externally of the cylinder block where they are readily accessible for renewal or repair, such bearings being those indicated at 10 and referred to above.

The inner ends of the pistons 19 are 65 rigidly secured to the parallel guide rails of

a transversely disposed rectangular frame 28 arranged within the crank case 6, and slidably mounted within the frame 28 is an eccentric strap in the form of a block 29 movable in the frame 28 transversely of the cylinders and pistons and having a circular central opening in which is disposed an eccentric 30 rigid with the portion of the shaft 21 that is exposed between the inner spaced ends of the sleeves 7. In this manner the eccentric block 29 is free to revolve about the eccentric 30 for a purpose which will presently become apparent.

The passages 22 and 23 preferably open through one end of the shaft 21, and any suitable means may be coupled to this end of shaft 21 for respectively conducting the air or gas to be compressed to the passage 22 and for conducting the compressed air or gas from the passage 23. Revolving of the cylinders and pistons about the shaft 21 may be effected by driving one of the sleeves 7 in any preferred manner, but for this purpose one of the sleeves 7 is preferably directly connected to the power shaft of a motor of any high speed type.

With the shaft 21 restrained from rotation and one of the sleeves 7 driven at a high speed of rotation, the cylinders and pistons will revolve about the shaft 21 and the frame 28 together with the eccentric block 29 will be carried around therewith so as to cause sliding movement of said block 29 transversely of the cylinders and pistons, and, by reason of engagement of the eccentric 30 in the block 29 the pistons 19 will be alternately moved inwardly and outwardly or reciprocated. When a piston moves inwardly it will uncover the passage 17 for permitting the air or gas to be drawn into the cooperating cylinder thereof, and when such piston is moved outwardly the passage 17 will be closed and the trapped air or gas will be compressed for unseating the valve 15 of such cylinder so that the compressed air or gas will be forced outwardly through the passage 18 into the passage 23.

The revolving cylinders will be cooled by reason of their revolving movement so that no water cooling system is required, and owing to the high speed at which the cylinders are revolved, a relatively large capacity compressor may be provided in accordance with this invention which is comparatively small in size. The structure is compact, simple and durable and characterized by elimination of undesirable pivoted parts such as connecting rods and the like that are employed in compressors now in common use.

From the foregoing description it is believed that the construction and operation as well as the advantages of the present invention will be readily understood and appreciated by those skilled in the art.

Minor changes may be made without departing from the spirit and scope of the invention as claimed.

What I claim as new is:

- 5 1. In a rotary compressor, a cylinder block embodying a pair of radial aligned cylinders connected by a crank case, sleeves rigid with and projecting outwardly from the crank case in horizontal aligned relation, means rotatably receiving the sleeves and supporting the latter and the cylinder block, a stationary shaft extending through the sleeves and about which the latter and the cylinder block are adapted to rotate, pistons reciprocable in said cylinders, a rigid guide frame to which the inner ends of the pistons are fixed, an eccentric block slideable in said frame, and an eccentric rigid with the shaft and having a block revolvably fitted thereon.

10 2. In a rotary compressor, a cylinder block embodying a pair of radial aligned cylinders connected by a crank case, sleeves rigid with and projecting outwardly from the sleeves and about which the latter and the cylinder block are adapted to rotate, a shaft extending through the sleeves, pistons reciprocable in said cylinders, a rigid guide frame to which the inner ends of the pistons are fixed, an eccentric block slideable in said frame, and an eccentric rigid with the shaft and having a block revolvably fitted thereon.

15 3. In a rotary compressor, a cylinder block embodying a pair of radial aligned cylinders connected by a crank case, sleeves rigid with and projecting outwardly from the sides of the crank case in horizontal aligned relation, means rotatably receiving the sleeves and supporting the latter and the cylinder block, a shaft extending through the sleeves and about which the latter and the cylinder block are adapted to rotate, pistons reciprocable in said cylinders, means operatively connecting the inner ends of the pistons with said shaft for causing reciprocation of the pistons when revolved about the shaft, said cylinder block and sleeves having exhaust and intake passages, said shaft having longitudinal exhaust and intake passages terminating in radial end portions opening through the side of the shaft within the respective sleeves and respectively in registry with the exhaust and intake passages of the latter, channel rings upon the shaft within the sleeves and having radial openings to place the passages of the shaft and sleeves in constant communication, and packing rings upon the shaft at opposite sides of said first named rings and within said sleeves.

20 4. In a compressor, a cylinder block embodying a pair of cylinders connected by a crank case, sleeves rigid with and projecting outwardly from the crank case in horizontal aligned relation, means supporting the sleeves and the cylinder block, a shaft extending through the sleeves, pistons reciprocable in said cylinders, a rigid guide frame to which the inner ends of the pistons are fixed, an eccentric block slideable in said frame, and an eccentric rigid with the shaft and having the block revolvably fitted thereon.

25 5. In a compressor, a cylinder block embodying a pair of cylinders connected by a crank case, sleeves rigid with and projecting outwardly from the sides of the crank case in horizontal aligned relation, means supporting the sleeves and the cylinder block, a shaft extending through the sleeves and the crank case, pistons reciprocable in said cylinders, means operatively connecting the inner ends of the pistons with said shaft for causing reciprocation of the pistons when a relative rotation is caused between the cylinder block and the shaft, an exhaust passage leading from the outer ends of the cylinders through a wall of the cylinder block and one of the sleeves in communication with the interior of the latter, an intake passage leading from the outer ends of the cylinders through a wall of the cylinder block and the other sleeve in communication with the interior of the latter, said shaft having longitudinal exhaust and intake passages terminating in radial end portions opening through the side of the shaft within the respective sleeves and respectively in register with the exhaust and intake passages of the latter, means to place the passages of the shaft and the sleeves in constant communication, and a packing between the shaft and the sleeves at opposite sides of the registered portions of the passages thereof.

30 6. In testimony whereof I affix my signature.
FRANK W. KNOWLES.
